The ornamental design for constant temperature cultivating apparatus, as shown.

(51) LOC (7) Cl. **10-04**

DESCRIPTION

(52) U.S. Cl. **D10/52**

FIG. 1 is a perspective view of constant temperature cultivating apparatus at the upper right-side direction;

(58) Field of Search D10/52; 73/865.6,

FIG. 2 is a front view thereof;

73/866, 54.01, 54.02, 54.04, 54.08, 54.09,
54.11, 54.14; 62/151, 176.5, 173, 186,
380, 180, 480; 324/500, 537, 760; 165/11.1,
11.2; 250/339.11, 373; 356/36, 364, 365,
317, 318, 300, 301

FIG. 3 is a rear view thereof;

FIG. 4 is a top view thereof;

FIG. 5 is a bottom view thereof;

FIG. 6 is a right-side view thereof;

FIG. 7 is a left-side view thereof; and,

FIG. 8 is a perspective view showing the status of opening
of a door of constant temperature cultivating apparatus.
